UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

RHEOSTAT.

SPECIFICATION forming part of Letters Patent No. 330,449, dated November 17, 1885.

Application filed December 27, 1884. Serial No. 151,310. (No model.)

To all whom it may concern:

Be it known that I, EDWARD WESTON, a subject of the Queen of Great Britain, and residing at Newark, in the county of Essex and 5 State of New Jersey, have invented certain new and useful Improvements in Rheostats, of which the following is a specification, reference being had to the drawings accompanying and forming a part of the same.

10 The subject of my present invention is a rheostat or artificial resistance, the nature and purpose of which will be understood by a general description of a system invented by me, and described by Letters Patent No. 15 304,882, dated September 9, 1884. In this or similar systems the lamps are run in multiple series, so that to maintain the same distribution of current at all times the relative resistances of the several branch circuits should 20 remain unchanged. If a lamp be extinguished therefore, an equivalent resistance must be substituted for it.

The lamps in the system referred to are of much larger size than those ordinarily used, 25 and consume a correspondingly greater amount of electrical energy. The resistance-coils used in place of these lamps must in consequence be capable of carrying the current without heating, and as a considerable number 30 are usually required it is important to make them as small and compact as possible. The objects which I had in view in the construction of this device are therefore to produce a rheostat which shall have a comparatively high resistance, which shall be capable of carrying a heavy current without heating, and which shall occupy but little space.

As the invention consists in the details of construction by which these results are attained, I will explain the same by reference to the accompanying drawings.

Figure 1 is a front elevation of a resistance-box constructed in accordance with my invention, a portion of the face or cover being cut away. Fig. 2 is a perspective of the frame for supporting the resistance-coils. Fig. 3 is a cross-section, on a reduced scale, of the box, showing the general arrangement of the resistance-wires.

50 The rheostat is contained in a box, A, con-

structed by preference so as to be placed on a shelf or attached to a vertical support. The box is covered by a perforated lid, B, and the sides may also be perforated, if it be so desired, to produce a better circulation of air.

55

The frame or support for the resistance-wires consists of a certain number of thin wooden or other like plates, C, held parallel to one another at short distances apart by four wooden bars, D. The plates or boards 60 C and bars D are secured together by glue, by screws, or otherwise, the bars being notched to receive the corners of the plates. The resistance-wire is formed in a long spiral, the length depending upon the resistance which 65 it is designed to offer, and this spiral is then wound around the several plates in the manner shown—that is to say, being made fast at one corner of the first plate, it is carried up on one side, the wire then straightened where it 70 passes over the edge of the board, as shown in Fig. 4. It is then carried down the opposite side of the board and up again on the other. When one board is filled with the spirals E, the wire is straightened and carried 75 over to the next board, and so on until all are covered, or the desired length of wire has been applied. A wire of German silver is commonly used.

While the peculiarities of the construction 80 of this device make it advisable to apply the wire in the manner described, this is not essential, as the spirals may be applied to each board separately, and afterward connected in series, or otherwise, as may be necessary. The 85 advantages secured by this construction are numerous. The spirals are very unlikely to become displaced or to come into contact with one another. All but the very smallest portion of the wire is exposed to the air, so that 90 the radiation of heat is fully provided for. The frame may be inserted in or drawn from the box with ease, so that in case of accident ready access may be had to the wires.

The device is a very cheap one and involves 95 no difficulties in its construction.

What I claim is—

1. A rheostat or artificial resistance consisting of insulating boards or plates supported by cross-bars, in combination with a 100

spiral wire wound around said boards or plates in the manner specified.

2. An insulating-frame consisting of boards or plates supported in parallel planes by 5 cross-bars secured to their corners and carrying a resistance-wire which, in the form of a spiral, is wound upon opposite sides of each plate, in combination with a box or receptacle

with perforations in one or more of its sides, as set forth.

In testimony whereof I have hereunto set my hand this 23d day of December, 1884.

EDWARD WESTON.
